US0D1013020S

(12) **United States Design Patent** (10) **Patent No.:** **US D1,013,020 S**
(45) **Date of Patent:** **** Jan. 30, 2024**

(54) **PROJECTOR**

(71) Applicant: **Xu Si**, Guangdong (CN)

(72) Inventor: **Xu Si**, Guangdong (CN)

(**) Term: **15 Years**

(21) Appl. No.: **29/896,425**

(22) Filed: **Jul. 3, 2023**

(51) **LOC (14) Cl.** **16-01**

(52) **U.S. Cl.**

USPC **D16/230**

(58) **Field of Classification Search**

USPC D16/221, 225, 230; D14/128, 129, 131;
D21/514, 515, 516

CPC G03B 21/00; G03B 21/12; G03B 21/14;
G03B 21/16; G03B 21/145

(57) **CLAIM**

The ornamental design for a projector, as shown and described.

DESCRIPTION

FIG. 1 is a front, right and top perspective view of a projector, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is an enlarged view of detail 10 in FIG. 3.

The broken lines depict portions of the projector that form no part of the claimed design.

The dot-dash broken lines shown in FIGS. 1, 3, 9, and 10 depict boundaries of the enlargements that form no part of the claimed design.

1 Claim, 10 Drawing Sheets
